(57) **CLAIM**

The ornamental design for a vehicle overhead console, as shown and described.

DESCRIPTION

FIG. 1 is an upward-looking view of a vehicle overhead console;

FIG. 2 is a close-up view of a front end portion called out in FIG. 1;

FIG. 3 is an upward-looking perspective view, from a left-side and forward-facing vantage;

FIG. 4 is the view of FIG. 4 showing a rear compartment cover in an open position;

FIG. 5 is the view of FIG. 5 showing a storage item positioned adjacent an item-receiving area of the rear compartment cover;

FIG. 6 is a left side view showing a front compartment cover and the rear compartment cover in open positions;

FIG. 7 is a right side view of FIG. 6; and,

FIG. 8 is the left side view, of FIG. 6, of the vehicle overhead console positioned in a vehicle.

Lines shown by dashed lines are provided for context and form no part of the claimed design.
